HEAT CONTROL DEVICE

Leonard W. Cook, Stratford, Conn., assignor to
General Electric Company, a corporation of New
York

Application August 28, 1942, Serial No. 456,509

5 Claims. (Cl. 200—122)

My invention relates to heat control devices and more particularly to devices for controlling electrically heated blankets and the like, and its object is to provide an improved control device of that character which is simple in construction, cheap to manufacture, and reliable in operation.

My invention will be better understood from the following description when taken in connection with the accompanying drawing, and its scope will be pointed out in the appended claims.

In the accompanying drawing, Fig. 1 is a front elevation view of one form of my improved heat control device; Fig. 2 is a sectional view of the device taken along line 2—2 of Fig. 1 and looking in the direction indicated by the arrows; Fig. 3 is a back view of the device with the back cover removed; Fig. 4 is a sectional view of the device taken along the line 4—4 of Fig. 3 and looking in the direction indicated by the arrows; Fig. 5 is the same view as Fig. 4 except the line switch is shown in its closed position; and Fig. 6 diagrammatically illustrates a blanket control system embodying my new control device.

Referring to the drawing, my control device 7 comprises a housing or base 8 of suitable insulating material, such for example as plastic or other molded material. This housing 8 is so formed that it constitutes the front and sides of my improved control device. The back of the housing 8 is arranged to be covered by a cover 9 that is fastened to the housing 8 by screws 10. An escutcheon plate 11 of suitable material, such as sheet brass, covers a portion of the front and bottom of the housing 8, this escutcheon plate being held in place by an extension 12 at the bottom thereof which extends upwardly along a portion of the back of the housing 8 below the cover 9 and by means of a metallic bushing 13 which extends through an opening in the front of the housing 8 and the escutcheon 11. One end 14 of the bushing 13 is enlarged and polygonal shaped and is inserted in a similar shaped opening in the inner surface of the housing so as to prevent rotation of the bushing. The other end 15 of the bushing 13 is spun over so as to hold the escutcheon plate 11 firmly against the outer surface of the housing 8. The plate 11 also constitutes means for conducting the heat from the interior of the housing so that the temperature therein follows more closely the ambient temperature changes.

The inner surface of the bushing 13 is threaded, and in threaded engagement therewith is a round hollow steel shaft 17 having a portion of its outer surface threaded for engagement with the inner threaded surface of the bushing 13. A knob 18

5 of suitable insulating material, such as plastic, is attached to the portion of the shaft 17 which protrudes from the front of the housing 8 in any suitable manner so that the shaft 17 may be readily rotated to cause it to be moved in or out relative to the front of the housing 8. The portion of the shaft 17 which protrudes from the bushing 13 toward the interior of the device 7 is knurled and also has a portion of its round surface flattened. 10 This portion of the shaft is surrounded by a collar 19 having two projections 20 and 21 spaced slightly less than 180 degrees apart. These projections 20 and 21 are arranged to engage a projection 22 extending toward the interior of the housing 8 so as to limit the rotation of the shaft 13 to substantially one-half of a revolution. In threaded engagement with the inner portion of the shaft 17 is a threaded screw 23 having a round head which projects toward the interior of the housing 8 from the inner end of the shaft. With the construction so far described, it will be observed that rotation of the knob 18 in one direction causes the rounded head of the screw 23 to move toward the back of the housing 8 and rotation of the knob 18 15 in the opposite direction causes the rounded end of the screw 23 to move toward the front of the housing 8.

20 The rounded end of the screw 23 engages a rectangular-shaped plate 24 of insulating material, one end of which, together with one end of a similar shaped brass plate 25 and one end of a bimetallic member 26 are riveted to a spring or flexible support 27, which in turn is secured to the inner side of the housing 8 by screws 28. The free end of the bimetallic member 26 carries a contact 29 which is arranged to engage a stationary contact 30 mounted near the end of one of the arms of an L-shaped member 31 of flat conducting material, such as brass, which is fastened to the housing 8 by a screw 32. Movement of the screw 23 as a result of rotating the knob 18 therefore flexes the spring support 27 so as to vary the position of the bimetallic member 26 and contact 29 with respect to the fixed contact 30. When the screw 23 is moved toward the back of the housing 27 in response to rotation of the knob 18, the screw 23 increases the temperature setting of the device, whereas when it is moved in the opposite direction, the temperature setting of the device is reduced.

25 In order to obtain a snap opening and closing of the contacts 29 and 30, the stationary contact 30 comprises a small U-shaped permanent magnet 33, preferably an Alnico magnet, soldered or otherwise secured to the member 31 and a flat con-

contacting surface 34 of suitable non-magnetic material such as silver, soldered or otherwise secured across the two pole faces of the magnet 33. The movable contact 29 is made of suitable magnetic material, such as steel, on which is secured by any suitable means, such as rolling or welding, a sheet of suitable contacting material 29', such as silver, so that a silver-to-silver contact is obtained when the contacts 29 and 30 are in engagement.

In order to obtain the proper temperature differential of operation, the stationary contact 30 is secured to the member 31 which is moved relatively to the movable contact 29 so as to change the amount of flux threading the magnet 33 and the magnetic material in the movable contact 29 to the proper amount to produce the desired calibration. Then member 31 is securely anchored by screw 32 at the position thereon that produces the proper calibration.

In order to materially reduce the effect on the temperature of the bimetallic member 24 of any arc established between the contacts 29 and 30, such heating effect is localized at the free end of the member 24 by restricting the cross-section of the portion of the member 26. This result is obtained in the arrangement shown by providing the holes in the bimetallic member 26 just above the contact 27 so that the thermal resistance between the contact 29 and the main body of the member 26 is high.

A small electric heater 35 of any suitable type is fastened to the inner surface of the portion of the housing 8 which constitutes the front of the heat control device 7 by suitable means, such as the screws 36. As shown, the heater 35 is arranged in the form of a coiled heater (not shown) encased within a hollow porcelain cylinder through which passes one of the leads 31 that supplies current to the heater 35. This heater 35, which has a relatively high thermal time constant is so located between the bimetallic member 26 and the housing 8 that the heating of the bimetallic member 26 varies in accordance with the current flowing through the heater 35.

In the lower portion of the housing 8 is located a manually controlled switch for opening and closing the circuit through the heating device whose temperature the control device 7 is arranged to control. This switch comprises a flat spring contact member 38 which is arranged to be moved into and out of engagement with a stationary contact 39 secured to the other arm of the L-shaped member 31 than the one to which the stationary contact 30 is secured. The spring contact member 38 comprises a spring blade, one end of which is secured to the inner surface of the housing 8 by a screw 40 and the other end of which has a contact 41 secured thereto. The spring member 38 is arranged to be flexed by means of a cam and operating trigger member 42 of suitable molded insulating material and provided with projecting cylindrical sections 43 which rotate in the housing 8. The trigger section of the member 42 consists of two sectors 44 and 45 which extend through an opening in the front of the housing 8 and which are so arranged that counterclockwise rotation of the trigger member causes the sector 44 to protrude from the front of the housing, whereas clockwise rotation of the trigger member causes the sector 45 to protrude from the front of the housing. One of these sectors, such as 44 for example, may be painted or otherwise marked in any suitable manner so that the condition

of the switch contacts may be readily observed merely by observing the color or the mark on the sector that protrudes from the front of the housing.

The cam section of the member 42 comprises a flat portion 46 arranged to be substantially parallel to the spring member 38 when the latter is in the open circuit position, as shown in Fig. 4, and another flat portion 47 which is arranged to be substantially parallel to the spring member when the latter is in its closed circuit position, as shown in Fig. 5. The member 42 also has a semispherical surface 48, preferably of steel, projecting from its surface at a point intermediate the two flat surfaces 46 and 47 and which moves into a hole 49 in the spring member 38 when it is in its open circuit position shown in Fig. 4.

The normal tension of the spring member 38 causes it to press forcibly against the member 42 at all times, and therefore it firmly maintains the trigger member 42 in each of its two positions. The member 42 is held within the housing 8 by an anchor plate 50 secured to the housing 8 by the screws 51 which anchor plate bears against the cylindrical sections 43 of the trigger member 42 thereby confining them within the bearing sections of the housing. The anchor plate 50 also has an extension 52 containing an opening 53 through which the spring member 38 extends. The top edge of the opening 53 acts as a fixed fulcrum point for the spring member 38 so that when the center section of the spring member is forced upward and away from the flat portion 46 of the cam member 42 by the semispherical member 48 moving out of the hole 49 and under the spring member 38 and by the positioning action of the surface 47 of cam 42 when the trigger member 42 is rotated clockwise from the position shown in Fig. 4, the free end of the spring member 38 is deflected downwardly so that the contact 41 on the spring member 38 engages the stationary contact 39, as shown in Fig. 5. Similarly, when the trigger member 42 is rotated in a clockwise direction from the position shown in Fig. 5 to the position shown in Fig. 4, the semispherical member 48 moves from under the spring member into the hole therein so that the normal tension of the member 38 causes the center portion thereof to move downwardly and the free end thereof to move upwardly about the edge of the opening 53 as a fulcrum so that the contact 41 is moved out of engagement with the stationary contact 39.

The control device 7 is arranged to be connected in the electric circuit to be controlled thereby by establishing a connection to a terminal 54 which is secured to and in electrical contact with the bimetallic member spring support 27 by one of the screws 28 and a connection to a terminal 55 which is secured to and in electrical contact with one terminal of the heater 35 by one of the screws 36. The electric connections of the various elements of the control device 7 will be more clearly seen from the diagram shown in Fig. 6 which illustrates a control system for an electric blanket embodying my control device. In this Fig. 6, 56 represents an electric blanket having a heating resistor 57, the ends of which are connected to a pair of terminal pins 58 that are adapted to be engaged by a pair of contacts 59 provided in a supply plug 60. The contacts 59 are respectively connected to the secondary terminals of a step-down transformer 61, the primary winding of which is con-

nected to a supply plug 62 through the control device 7. From Fig. 6 it will be seen that when the trigger member 42 of the control device 7 is in the position shown in Fig. 5, the primary winding of the transformer 61 is connected in series with the bimetallic member 26, contacts 29, 30, 38, and 41, the spring member 38, and the heater 35. Therefore, when the trigger switch is in the position shown in Fig. 5, the electric energy input to the blanket 56 is controlled by the proportion of time that the contacts 38 and 41 are in engagement to the time that these contacts are out of engagement. These times are controlled by the temperature of the bimetallic element 24, which is jointly dependent upon the room temperature and upon the heat supplied to the bimetallic element from the auxiliary heater 35. For a given unchanging room temperature, the bimetallic element 26 controls the time of engagement of the contacts 29 and 30 so as to maintain the temperature of the blanket at a substantially constant value. When the room temperature varies, however, the amount of energy input into the blanket is varied since thus, if for a given setting of the control device, the room temperature should decrease, the heat that would be imparted to the bimetallic element 24 from the room is reduced and therefore it requires a longer period of time for the auxiliary heater 35 to heat the bimetallic member 26 to the temperature at which it causes the contacts 29 and 30 to disengage than it did before, and after these contacts have opened and the auxiliary heater 35 is deenergized, the thermostatic element will cool quicker to cause the contacts to reengage due to the increased cooling action of the room. These two actions of delaying the separation of the contacts and in advancing their closing result in an increase in the proportion of time that the contacts are in engagement over any given interval of time. The control, therefore, supplies more energy to the blanket during a given time interval so as to maintain the temperature of the blanket at a predetermined value in spite of the decrease in room temperature. Conversely, when the room warms up, the proportion of time that the contacts 29 and 30 are in engagement to the time that they are out of engagement is decreased so as to decrease the total amount of energy supplied to the blanket during a given time interval.

The transformer 61 functions to reduce the voltage of the supply line to a relatively low value so as to eliminate any danger of shock by the user of the blanket.

While I have, in accordance with the patent statutes, shown and described my invention as applied to a particular construction and as embodying various devices, changes and modifications will be obvious to those skilled in the art, and I therefore aim in the appended claims to cover all such changes and modifications as fall

within the true spirit and scope of my invention. What I claim as new and desire to secure by Letters Patent of the United States is:

1. In combination, a housing of insulating material, a bimetallic member having one end fastened to said housing and an electric contact mounted on the other end thereof, a stationary contact secured to said housing and adapted to be engaged by said first mentioned contact, said first mentioned contact being of a magnetic material having a contacting surface of suitable material and said stationary contact comprising a magnet having a contact of suitable non-magnetic material secured across the poles of said magnet and forming the contacting surface thereof engaged by said first mentioned contact.
2. In combination, a fixed support, a bimetallic member having one end fastened to said support and a contact mounted on the other end thereof, a stationary contact arranged to be engaged by said first mentioned contact to establish a series circuit through said member and said contacts, and means for localizing the heating effect on said bimetallic member of any arc established between said contacts.
3. In combination, a fixed support, a stationary contact, and a movable contact mounted on one end of a bimetallic member, the other end of said member being fastened to said support, said member being of relatively small area adjacent to the point where said movable contact is mounted thereon in comparison to the main body of said member in order to establish high thermal resistance to the transmission to the main body of said member of heat developed by an established arc between said contacts.
4. In combination, a housing of insulating material, a bimetallic member having one end thereof fastened to said housing and an electric contact secured to the other end thereof, a stationary contact secured to said housing and arranged to be engaged by said first mentioned contact, a heater interposed between said bimetallic member and the inner surface of one side of said housing, and a metallic plate held in contact with the outer surface of said one side of said housing and functioning to radiate the heat supplied to said one side of said housing by said heater.
5. In combination, a housing of insulating material, a bimetallic member having one end thereof fastened to said housing and an electric contact secured to the other end thereof, a stationary conducting member secured to said housing and having a contact secured thereto for engagement by said first mentioned contact, a fixed contact secured to said conducting member, a movable contact attached to said housing, and a cam rotatably mounted in said housing for moving said movable contact into and out of engagement with said fixed contact.

LEONARD W. COOK.
